Patented Dec. 11, 1917.

W. M. de Pars.

INVENTOR,
William M. de Pars,
John Stewart,
ATTORNEY.

UNITED STATES PATENT OFFICE.

WILLIAM M. DE PARS, OF PATERSON, NEW JERSEY.

GAME APPARATUS.

1,249,915.

Specification of Letters Patent. Patented Dec. 11, 1917.

Application filed May 14, 1917. Serial No. 168,603.

To all whom it may concern:

Be it known that I, WILLIAM M. DE PARS, a citizen of the Republic of France, residing at Paterson, in the county of Passaic and 5 State of New Jersey, have invented certain new and useful Improvements in Game Apparatus, of which the following is a specification.

This invention relates to games or toys 10 and it consists in certain combinations and arrangements of parts whereby an apparatus is produced that will not only afford amusement to the players and improve their faculties in respect to visual judgment and 15 manual skilfulness but may be manufactured so as to be substantial and durable and yet capable of being marketed at a comparatively small expense. To this end my invention includes a movable support having 20 a wall extending in the direction of movement of the support and formed with an aperture in the wall, an object to be actuated movably sustained on the support and having a part thereof arranged at one side 25 of said wall and opposite the aperture, and means, with reference to which said support moves and arranged at the other side of said wall opposite the path of movement of the aperture, for discharging a projectile 30 through the aperture of the moving support thus to actuate the object. In the preferred form, the support rotates on a vertical axis and has a horizontal top wall and a cylindrical wall depending from the top wall 35 and extending around said axis, such cylindrical wall being formed with the aforesaid aperture and the part of the object which is opposite the aperture being within the cylindrical wall, and the means for discharging 40 a projectile is exterior of the cylindrical wall, the object of this construction being to limit the progress of the projectile after it passes through the aperture and thus insure 45 its delivery into suitable means provided below the support for its reception.

In the accompanying drawing,

Figure 1 is a plan view of the apparatus; and

Fig. 2 is a side elevation, partly in section. 50 *a* designates a suitable cabinet or case having a lower horizontal or bottom wall *b* and an upper horizontal wall *c* forming a lower compartment *d* and an upper compartment *e*, the latter compartment being open at 55 the top.

In suitable bearings in the walls *b* and *c*

is journaled a vertical shaft *f* which carries, preferably somewhat above the side walls *g* of the cabinet, the support *h*, which has a horizontal disk-shaped top wall *i* (by which 60 the support is directly affixed to the upper end of the shaft) and a depending cylindrical flange or wall *j*. The wall *j* is formed at suitable, preferably regular, intervals, with apertures *k*, registering with each of 65 which there is preferably provided an inwardly projecting thimble or tubulure *l*.

On the top of the wall *i*, at intervals corresponding with those of the apertures *k*, are pivoted the objects *m*, here taking the form 70 of war vessels in miniature. They are pivoted to the wall *i*, on horizontal axes, by means of the eyes *n* or otherwise, and each has a depending arm *o* which extends through an opening *p* in the wall *i*. Each 75 arm *o* is in the same radial line as the corresponding aperture *k*, and when the object *m* is in an upright position the arm bears against the outer edge of the opening *p* and so supports the object slightly canted inwardly from the perpendicular; the object 80 may fall outwardly, as upon its arm receiving an impact from a point radially outwardly thereof, to the position shown by dotted lines in Fig. 2, in which position its 85 arm is folded against the under side of the wall *i*.

The means for discharging a projectile or projectiles through the aperture *k* and against the arms *o* of the object *m* may be 90 thus described: In radii from shaft *f* and spaced at intervals the same as the apertures *k* there are mounted on supports *q*, upstanding from the cabinet *a*, several spring guns. Each of these consists of a barrel *r* having 95 a plunger *s* which is normally pressed rearwardly by a light spring *t*. When the plunger is fully retracted it uncovers an opening *u* at the top of the barrel, which opening may be closed by a removable plug 100 *v*. A plate spring *w* is attached to the cabinet and upstands back of the plunger, normally overcoming spring *t* and holding the plunger forward. The mouth of each gun is close to the wall *j* of the support *h*, and the 105 gun inclines slightly in the outward direction.

x is the projectile, being preferably a ball which will pass through the opening *u* but will not pass between the mouth of the gun 110 and the wall *j* of support *h*.

A motor to drive the shaft *f* and conse-

quently support *h* is preferably provided. Any form of motor will do that will drive the shaft at a relatively low speed, that shown in the drawing consisting of a spool 5 *y* on which are reversely wound two cords *z* which are passed through suitable openings 2 in the side walls *g* of the cabinet and have means 3 to carry a weight or weights 4 that may be transferred from one to the other.

10 The cabinet, if desired, may be supported on folding legs 5.

It will be understood that, the support *h* being rotated with the several objects *m* arranged in upstanding position, the object is 15 to employ the guns to discharge the projectiles through the apertures as they pass the muzzles of the guns, thus to cause the projectiles to strike the arms *o* of and knock down the objects. Each projectile is introduced into a gun by removing its plug *v*, having first withdrawn the plate spring *w* so that the plunger will be forced back clear 20 of the opening *u* by its spring *t*. To discharge the gun, the drawn-back plate spring 25 is released, overcoming the resistance of the spring *t* and snapping the plunger inward. If the projectile should fail to enter an aperture *k* it would strike against the wall *j* and in any event will recede as far as the 30 plunger allows it on account of the outward incline of the gun. The projectile cannot fall between the muzzle of the gun and the wall *j* because its diameter is greater than the distance between them. If a projectile 35 is discharged through an aperture *k*, it will strike the opposite side of wall *j* and so fall into the compartment *e*.

If desired, the objects *m* may be differentiated, as by color, or otherwise, so that with 40 several players the purpose would be for each player to knock down some particular object *m*.

The support may be rotated by the motor shown in the drawings by transferring the 45 weight 4 from one to the other of the weight carriers 3, as will be obvious.

The apparatus may for the most part be made of papier-mâché, or wood or other light and inexpensive material, as will be 50 obvious.

Having thus fully described my invention, what I claim as new and desire to secure by Letters Patent is:—

1. In a game apparatus, a movable support having a wall extending in the direction of movement of the support and an aperture in said wall, an object to be actuated movably sustained on the support and having a part thereof arranged at one side 55 of said wall and opposite the aperture, and means, with reference to which said support moves and arranged at the other side of said wall opposite the path of movement of

the aperture, for discharging a projectile through the aperture.

2. In a game apparatus, a rotary support having a wall extending around its axis of rotation and an aperture in said wall, an object to be actuated movably sustained on the support and having a part thereof arranged within said wall and opposite the aperture, and means, with reference to which said support moves and arranged exterior of said wall opposite the path of movement of the aperture, for discharging a projectile 75 through the aperture.

3. In a game apparatus, an upwardly open cabinet, a rotary support journaled therein on a vertical axis and having a wall extending around its axis of rotation and an aperture in said wall, an object to be actuated movably sustained on the support and having a part thereof arranged within said wall and opposite the aperture, and means, with reference to which said support moves and 80 arranged exterior of said wall opposite the path of movement of the aperture, for discharging a projectile through the aperture.

4. In a game apparatus, a movable support having a wall extending in the direction 90 of movement of the support and an aperture in said wall, an object to be actuated movably sustained on the support and having a part thereof arranged at one side of said wall and opposite the aperture, a gun 95 at the other side of said wall and with reference to which said support moves, the gun having its muzzle opposite the path of movement of the aperture and close to said wall, and a projectile for the gun of a diameter 100 less than the aperture but greater than the space between the gun muzzle and said wall.

5. In a game apparatus, a movable support having a wall extending in the direction of movement of the support and an 105 aperture in said wall, an object to be actuated movably sustained on the support and having a part thereof arranged at one side of said wall and opposite the aperture, a gun at the other side of said wall and with reference to which said support moves, the gun 110 being outwardly inclined and having its muzzle opposite the path of movement of the aperture and close to said wall, and a spherical projectile for the gun.

6. In a game apparatus, a rotary support journaled on a vertical axis and having an upright wall and an aperture in said wall, an object to be actuated movably sustained on the support and having a part thereof 120 opposite the aperture, and means, with reference to which said support moves, for discharging a projectile through the aperture and against said part.

In testimony whereof I affix my signature. 125
WILLIAM M. DE PARS.
